MOBILE BOOK RACK AND STORAGE BOX COMBINATION

Vernon M. Hemingway, 913 Norby St.,
Carson, Calif. 90746

Filed July 18, 1975, Ser. No. 597,065

Term of patent 14 years

Int. Cl. D6—06

U.S. Cl. D6—184

FIG. 1

FIG. 2

FIG. 3

FIG. 1 is a pictorial view of a mobile book rack and storage box combination showing my new design, the opposite side being similar;

FIG. 2 is a front elevation thereof, the back side being similar; and

FIG. 3 is a side elevation thereof, the opposite side being similar.

The bottom view of my novel design is plain and is not shown, while the casters thereon are of standard design.

I claim:

The ornamental design for a mobile book rack and storage box combination, as shown and described.
